F. C. NELSON.
NEEDLE THREADER.
APPLICATION FILED JUNE 1, 1920.

1,371,429.

Patented Mar. 15, 1921.

INVENTOR

Fred C. Nelson
BY
George F. Voight
ATTORNEY

UNITED STATES PATENT OFFICE.

FRED C. NELSON, OF OAKLAND, CALIFORNIA.

NEEDLE-THREADER.

1,371,429.

Specification of Letters Patent. Patented Mar. 15, 1921.

Application filed June 1, 1920. Serial No. 385,547.

To all whom it may concern:

Be it known that I, FRED C. NELSON, a citizen of the United States, residing at Oakland, in the county of Alameda and State of California, have invented new and useful Improvements in Needle-Threaders, of which the following is a specification, reference being had therein to the accompanying drawings.

10 My invention relates to needle threaders embodying a frame carrying a hook adapted to be projected through the eye of a needle for picking up the thread, which may then be drawn through the needle's eye by 15 simply withdrawing the hook.

One of the objects of my invention is the provision of a novel stamping in sheet metal from which the frame is constructed.

Another object is to provide novel means 20 for securing the hook to the frame.

Still further objects of the invention will appear as the description proceeds.

In the drawings—

Figure 1 is a side elevation of my improved needle threader.

Fig. 2 is a longitudinal sectional view of the device.

Fig. 3 is a sectional view on line *a—a*, Fig. 1.

30 Fig. 4 is a sectional view on line *b—b*, Fig. 1.

Fig. 5 is a stamping in blank of a portion of the device.

Fig. 6 is a view the same as Fig. 5, with 35 the threading hook disposed in its position at one end of the stamping.

Fig. 7 is a view of the stamping and hook shown in Fig. 6, after the stamping has been doubled upwardly to secure one end 40 of the hook.

Fig. 8 is a view in section on line *c—c*, Fig. 7.

Fig. 9 is a stamping in blank of a portion of the frame.

45 Fig. 10 is a sectional view on line *d—d*, Fig. 1.

Referring to the drawings in detail, throughout which like reference characters designate like parts—

50 The numerals 1 and 2 designate a pair of spaced apart flat side pieces, unitarily connected together at their lower edges as at 3, of a frame designated by the numeral 4.

In Fig. 9 is illustrated a blank stamping 55 of the frame 4 before the side members 1

and 2 have been struck upwardly, as best depicted in Figs. 1 and 10.

In striking the stamping, illustrated in Fig. 9, from sheet metal stock, I provide a pair of openings 5 and 5^a, of equal diameters, spaced equal distances from one end of the stamping and equal distances from the respective side edges thereof. At the opposite end of the stamping is cut a slot 6 having parallel sides 7 and 8, and a semi-circular end 9. The arrangement of said openings and slot is such that when the frame has been struck into shape as in the finished article as best depicted in Fig. 1, the openings will be oppositely disposed 70 and in axial alinement with each other, and the slot at the other end will form an under-crop 10 in the lower edge of the members 1 and 2, in which the sides 7 and 8 extend parallel with the upper edges of said members, and said semi-circular end 9 forms a line describing a quadrant extending approximately from a point formed by about the 280th degree of a circle to the 360th degree thereof.

80 The under-crop 10 is primarily adapted to form a vertical slot or opening 11 extending from the upper to the lower edges of the frame, thereby forming a pair of spaced apart tongues 12, 13, between which tongues 85 the upper portion of a needle indicated in the drawings by the letter A, and provided with an eye designated by B, may be made to operatively slide. D designates thread.

The free ends of the members 1 and 2 90 are bent outwardly as at 14 to permit the needle A a freer entrance into the slot 11.

15 is a sheet metal stamping, shown in blank in Figs. 5 and 6.

16 designates the upper shank, 17 the 95 lower shank, and 18 the crooked end, of a threading hook. The shank 16 is disposed, approximately at an angle of 45 degrees from the horizontal, upon one side of the stamping 15, in which position it is intended to be rigidly clamped by doubling the member 15 upwardly as shown in Figs. 7 and 8.

After the member 15 has been doubled as aforesaid, it is inserted between the members 1 and 2 (see Fig. 4), after which its free end is struck to one side over the top edge of the member 1, thence down along one side thereof and up along the outer side of the member 2. It is intended that the 110

aforesaid assembly of said parts, including the shank 16, shall rigidly secure them together.

The shank 17 projects outwardly below the under-crop 10, in a vertical plane with the slot 11, and at an angle downwardly from a horizontal plane extending through the point of intersection of said shank with the shank 16.

10 To operate my needle threader, the upper end of a needle A is inserted between the members 7 and 8 and the crooked end 18 projected through the eye B to engage the thread D (see Fig 1). The needle is then 15 withdrawn over the thread as shown in Fig. 2. After which the hook is disengaged from the thread and the operation completed.

It is to be understood that changes in the precise embodiment of the invention as 20 shown and described can be made within the scope of what is claimed without departing from the spirit of the invention.

Having described my invention what I claim as new and desire to secure by Letters 25 Patent, is:

1. A needle threader of the class described, embodying a frame comprising a pair of flat side pieces spaced a distance apart and extending parallel with each 30 other, the lower edges of the side pieces unitarily connected together, the arrangement thereof being such as to form a U in cross section having arms vertically extended, a reinforcing ribbon having a portion disposed between said side pieces intermediate their ends and another portion embracing them by engaging their outer sides, an under-cut on the lower side of the frame extending from one end thereof to 35 said reinforcing ribbon, the free ends of said end of the frame being bent outwardly in directions away from each other, and a hook disposed in said under-cut and having one end rigidly secured to said ribbon between said side pieces.

40 2. In a device of the kind described, the combination with a frame comprising two flat side pieces, sides of said pieces disposed in close relation with each other, the lower 45 edges of the side pieces rigidly connected together, the arrangement being such as to form a U in cross section having arms vertically extended, of a sheet metal ribbon having one end doubled back upon itself and 50 embracing one end of the shank of a hook,

said end of the ribbon disposed between the arms of the U, the other portion of said ribbon embracing the frame laterally, an under-cut on the lower side of the frame between said ribbon and one end of the side 60 pieces, the free end of said shank projecting into said under-cut and disposed in a vertical plane extending longitudinally through the frame, and a thread engaging a crook at 65 said free end of the hook shank.

3. A needle threader embodying a frame comprising a pair of flat side pieces spaced a comparatively short distance apart with one of the flat sides of one next to one of the flat sides of the other thereof, the lower 70 edges of said side pieces unitarily joined together; the arrangement being such as to form a U in cross section having arms vertically extended, a sheet metal ribbon having one end folded backwardly forming 75 thereby a U having one of its arms substantially longer than the other, a hook shank having one end disposed between said fold, said folded end of the ribbon disposed between said side pieces intermediate the ends 80 thereof, the lower end of said last mentioned U terminating short of the lower edge of the frame, the free end of said long arm folded laterally of the frame over the free end of the short arm and laterally over the 85 upper edge of one of said side pieces and downwardly along the outer side thereof to the outer side of the other side piece terminating adjacent the upper edge of the latter, the arrangement being such that said 90 long arm may embrace said side pieces to cause them to clamp said folded end together upon said hook shank to rigidly secure it therebetween, an under-crop cut in the lower edge of the frame and extending 95 from one end thereof to a point adjacent said ribbon, the free end of said hook shank projecting into said under-crop, said free end diverging downwardly at a slight angle 100 from the horizontal and disposed in a vertical median plane extending longitudinally through the frame, and a thread engaging crook on said free end of the hook shank, the outer or free end of said hook shank disposed at an angle with the inner or secured 105 end thereof.

In witness that I claim the foregoing as my own, I have hereunto signed my name this 4th day of May, 1920.

FRED C. NELSON
